SHOE HEEL

Ralph Caiazzo, Brooklyn, N. Y.

Application March 15, 1932, Serial No. 599,003

1 Claim. (Cl. 36—34)

This invention relates to improvements in shoe-heels; the invention having a plurality of utilities especially applicable to ladies' shoe-heels. However, the invention is not to be limited to ladies' shoe-heels, and may, of course, be applied to men's and children's shoe-heels.

It is well known that shoe-heels, whether or not having a familiar type of rubber heel at the bottom wear away unevenly practically always on one side of the foot or the other. Because of differing strides and manners of walking of different persons, such wearing away of the lower leather lift or of the bottom rubber heel varies. In any case, however, such lift or rubber heel wears away unevenly. When this uneven wear has progressed to such an extent that one side of the heel is about $\frac{1}{8}$ " higher than the other, this condition, proverbially spoken of as "run down at the heel", with all its familiar connotation of lack of financial well-being or social carelessness, is noticeable even to the casual observer. Most persons are desirous of maintaining their foot-wear in other than this condition at all times, and would immediately, were the condition brought to their attention properly, visit a shoemaker and have the heel bottom straightened by a replacement of the worn-away part.

One of the objects of the present invention
30 is to provide a shoe-heel so built up as to in-
clude means for always giving instant notice to
the wearer that it is time to visit the shoemaker
for the purpose of such replacement, with pref-
erably such means so constituted that it per-
35 forms other useful functions as well.

Rubber shoe-heels have come largely into favor for their comfort and quiet. Rubber, however, is comparatively expensive; and the best grade of pure and highly elastic rubber is desirable for the making of rubber shoe-heels.

40 SUBJECT TO THE MAKING OF RUBBER SHOE-HEELS.
Another object of the present invention is to provide a shoe-heel, as above described, wherein said means is so combined with the other parts of the new heel that, when straightening of the
45 heel is required due to its wearing down to about the limit above mentioned at one side or the other, the replacement unit required has a bulk of rubber (or leather) approximately equal to, or even somewhat less than, half that of the
50 usual rubber heel.

A further object of the invention is to provide a shoe-heel so composited or built up as to include the means aforesaid, and a plurality of lifts, or layers, of rubber or leather or the like, or one, say, of rubber and the other of

leather; with these parts so combined that one of such lifts or layers, applied directly to the bottom of the wooden or other shoe-heel of a ladies' shoe, or equivalently to the bottom of the heel of any shoe, is always maintained in that location, and is always protected by said means against contact with the pavement to wear away or otherwise injure the same.

Still another object of the invention, especially for ladies' shoes, is to provide a shoe-heel built up so as to include the means aforesaid, and wherein a new decorative effect is achieved by virtue of the general assembly, and particularly by the appearance and ornamentation possibilities of the part, or parts, of said means which is, or are, exposed while the shoe is on the foot of the wearer. In this aspect, the invention constitutes an improvement over the ladies' shoe-heels disclosed and claimed in U. S. patent to me No. 1,794,944. 75

Other objects and advantages of the invention will be hereinafter specifically pointed out, or will become apparent as the specification proceeds.

In the form of my invention which I now consider best, the shoe-heel comprises a shell, desirably of metal, shaped at its periphery to follow the outline of the heel, and cupped, dished or otherwise suitably shaped on opposite sides for a fitting to each of such shapings of one of two lifts of leather, rubber or the like, so that a main flat web of said shell lies horizontally; said shell being so formed as to assist in positioning the lifts interlockingly of web shapings, and in securing the lifts and the shell as one unit, yet a highly resilient unit if one or more of the lifts be of rubber, to the bottom of the heel, as by nails of familiar type passing through all three elements. Also, in this approved form of the invention, the shell bottom includes a cup formed in part of a depending skirt following the outline of the heel; the bottom line of which skirt when the unit has a new bottom lift lies about $\frac{1}{8}$ ", or other suitable and intended distance, above the bottom of the lift last mentioned. The thus-exposed skirt, particularly when scalloped, indented, or similarly shaped along its lower edge, forms at once a decorative adjunct and a warning appliance, functioning in this latter regard by giving a discordant scraping sound to the ears and a jar to the foot of the wearer of the shoe when said bottom lift becomes so unevenly worn away at one side or the other as to approach shabbiness of shoe appearance.

A preferred embodiment of the invention is ac. 110.

cordance with the foregoing paragraph is illustrated in the accompanying drawing, in which:

Fig. 1 is a view in side elevation showing said embodiment applied to a ladies' wooden shoe-
5 heel;

Fig. 2 is a top plan view, somewhat enlarged, showing said embodiment removed from said heel;

Fig. 3 is a transverse section taken on the line
10 3—3 of Fig. 2;

Fig. 4 is a bottom plan view of the shell;

Fig. 5 is a top plan view of said shell;

Fig. 6 is a bottom plan view of the upper lift;
and

15 Fig. 7 is a similar view of a modified form of bottom lift.

A familiar type of ladies' wooden shoe heel is indicated at 10.

Referring to the form of the invention illustrated in Figs. 1 to 6, the shoe-heel shown includes a bottom lift 11, preferably of rubber, an intermediate shell 12, preferably of steel, and an upper lift 13, preferably of rubber.

The shell 12 has a web portion 12a provided with a central opening 12b of the shape shown as the result of taking away all metal except that required marginally of the web and that required to establish three projections 12c, 12c', and 12c'', each having a nail hole 12d therethrough. The marginal portion of the web is dished into an upper convexity, thus constituting a shaping 12f for entering and inter-fitting with a properly formed concavity in the bottom of the upper lift 13. Beyond the web, the shell 12 has a depending skirt 12g, making of the bottom of the shell a cup into which is entered the upper portion of the bottom lift 11. In the arrangement shown, this causes the lower portion of said lift to protrude somewhat less than $\frac{1}{8}$ " below the bottom of the skirt 12g.

Since considerable grinding or twisting stress is imparted to the lower or tread surface of the bottom lift 11 during walking, said lift is additionally interlocked with the shell by molding or 45 otherwise forming said lift so that the latter carries on top thereof, a flat topped projection shaped to fit nicely within the central opening 12b of the shell or the upper lift 13 may be provided with a lower projection 13a as shown in Fig. 3 to fit in said opening 12b.

Nails 14 or the like sent through the lower lift, nevertheless, pass through the web of the shell by way of the holes 12d, and also through the upper lift and into the wooden heel 10.

When the lower lift has become so unevenly, or, in the rare case, evenly worn away as to cause the skirt 12g to act, as hereinabove explained, as a warning device, the nails 14 are withdrawn, the lift 11 discarded, and, with a new lower lift substituted therefor, the same or similar nails are again applied, as just described, to remount the unit on the wooden heel 10. This is a quick operation, due to the inter-fitting of the parts 11, 12, 13, as above pointed out, so that the unit of the invention may be handled easily and without special care against accidental shifting of one part of the unit relative to another. In order at the same time to insure instantaneous proper fitting of the upper side of the upper lift 13 to the under side of the wooden heel 10, said upper

lift, as shown, has integrally molded therearound an up-standing marginal bead or ridge 13a' forming a cup receptor for the bottom of the wooden heel. Such, or an equivalent, shaping of the upper portion of the upper lift 13 may be dispensed with; but the same is preferred for the purpose just mentioned, and also for adding a novel, decorative effect to the bottom of the shoe-heel, particularly in the case of a ladies' shoe.

The skirt 12g of the shell is here shown as having its lower edge scalloped, giving one possible decorative effect. Such skirt may be otherwise shaped, for instance, given a straight or wavy lower edge. Whatever its edge shaping, it may have its exposed surface given any desired decoration, as by chasing, stamping, piercing, enameling, jewel-insetting, or otherwise. The surface or applied decoration may be one color or varicolored. Whether the skirt surface is plain or embellished, the same may have any desired finish. For instance, if the shell is of brass, as it may well be, it may be merely polished, or nickel or chromium plated.

Referring to the modification shown in Fig. 7, with the upper lift and the shell as above described, the lower lift can be so shaped as to utilize all or a part of the opening 12b in the web of the shell as a means for providing between the two lifts one or more sealed compartments for pocketing air therein thereby to increase the cushioning effect of the new unit by interposing air cushions. For example, two such compartments will be provided when a lower lift is employed which is shaped as shown in Fig. 7. At the same time, the interlocking of that lift with the shell by way of a flat topped projection on the top of the lift will, nevertheless, be obtained. The lift 13' of Fig. 7, it will be noted, has such projection, which is marked 13'', shaped in such way that the projection is elongated lengthwise of the shoe with an indentation at one end and with such end inter-fitting with the projection 12c and the opposite end inter-fitted between the projections 12c' and 12c'' of the web of the shell. When the parts are thus assembled, the outline of the opening in the shell is as indicated in dot and dash lines in Fig. 7. Thus, air cushion compartments will be provided in the assembled unit at 15 and 15a.

The hereinbefore described construction admits of considerable modifications without departing from the invention; therefore, I do not wish to be limited to the precise arrangements shown and described, which are, as aforesaid, by way of illustration merely. In other words, the scope of protection contemplated is to be taken solely from the appended claim, interpreted as broadly as is consistent with the prior art.

What is claimed is:

A composite heel including a pair of lifts, and an interposed element of comparatively rigid material, said element having downturned portions terminating intermediate the top and bottom of the lift therebelow, the upper lift having at its upper side a marginal ridge to provide a cup-shaped receptor for the bottom of the heel proper.

RALPH CAIAZZO.
